UNITED STATES PATENT OFFICE

2,474,121

CONTROL OF FUEL-INJECTION ENGINES

Arthur Freeman Sanders, Penzance, England

Application April 16, 1947, Serial No. 741,807
In Great Britain September 9, 1942Section 1, Public Law 690, August 8, 1946
Patent expires September 9, 1962

3 Claims. (Cl. 123—140)

1

This invention relates to a fuel-injection engine such as has a device, responsive to the lubrication pressure of the engine, which is associated directly or indirectly with the main fuel control member of the fuel pumping unit so as to cut off the fuel delivery if the lubrication pressure falls below a predetermined value.

According to the invention, the device also limits the maximum fuel delivery in running conditions. Furthermore, the device is preferably adapted also to provide an excess fuel delivery (beyond the normal maximum) at starting.

In the accompanying drawings:

Figure 1 is a sectional elevation of a device according to the invention;

Figure 2 is a plan thereof; and

Figure 3 is a fragmentary elevational view showing an alternative means of operation.

In the construction shown the device is carried by a bracket 10 bolted or otherwise secured against an appropriate wall of the fuel pumping unit 11, the device comprising a vertical cylinder 12 connected at its lower end to a pipe 13 leading to the lubrication system of the engine (not shown) so as to receive the pressure thereof. In the cylinder is disposed a plunger 14 biased downwardly by a combined torsion and tension spring 15, a stop being provided to limit the outward movement of the plunger. The latter has a cylindrical portion 16 outside the cylinder, and above that a truncated cone portion 17, which parts can coact, dependently upon the lubrication pressure, with a roller 18 carried at the end of the main fuel control member 19 of the pump unit. On one side of the truncated cone portion is milled a slot 20 of a width to receive the roller, the bottom of the slot curving out to join the cylindrical portion 16 of the plunger.

Normally the slot is away from the roller, as shown by Figure 1, and when the engine is stationary the roller engages the upper end (maximum diameter) of the truncated cone portion, the fuel delivery then being cut off, as shown by the full lines. To start the engine the plunger is turned through 180° to bring the slot 20 of the truncated cone portion into alignment with the roller, thus subjecting the biassing spring 15 to a torsional stress, and the main fuel control member 19 can then be forced by the normal governor spring into a position in which excess fuel, beyond the normal maximum, can be delivered by the pump unit. When the engine is started it will increase in speed until the governor comes into play, moving the main fuel control member towards the closed position—i. e., to carry

2

the roller to the left (Figure 1) and out of the slot 20. Also, the lubrication pressure building up beneath the plunger will force this outwardly against the tension of the biassing spring 15 until the roller is quite clear of the slot 20, and, in fact, the cylindrical portion 16 of the plunger is in line with the roller, as shown by the chain lines of Figure 1. The cylindrical portion 16 will then determine the maximum fuel delivery as long as the lubrication pressure is maintained. When the roller is quite clear of the slot 20 the torsion of the spring 15 will twist the plunger to move the slot out of alignment with the roller, i. e., back to the position of Figure 2.

15 In the event, however, of the lubrication pressure failing, the spring acting upon the plunger will return the parts to the engine-stationary position shown by the full lines of Figure 1, the inclined surface of the truncated cone portion 20 acting on the roller to force the main fuel control member 19 to the fuel cut-off position. The roller may be supported against side thrust as necessary.

To stop the engine the plunger can be pushed down manually and held down until the engine is stopped; and, if desired, provision may be made for effecting this, or for turning the plunger to the starting position, from the dashboard or the like accessible place in the case of a motor-vehicle having an engine fitted with the device of the invention.

A remote control means is illustrated in Figure 3, in which the plunger is shown in the stop position. The end 22 of a Bowden or like control is wound round and appropriately secured to an exposed portion of the plunger. In addition, a Bowden or like control 23 is connected to a lever 24 the free end of which is adapted to coact with the head of the truncated cone portion 17 of the plunger. The drawing shows the parts when the control 23 has been pulled to cause the lever 24 to force the plunger downwardly against the oil pressure, thereby stopping the engine. By means of the control 22 the plunger can be rotated through 180° to bring the slot 20 into co-operation with the roller 18, whereby to place the main fuel control member in the starting position, as above described. As the engine starts the roller 18 will tend to be withdrawn from the slot 20 and the oil pressure will tend to lift the slot 20 clear of the roller, such that the plunger can be turned by the spring 15 back to the normal running position—assuming, of course, that the control 22 has not been held in the starting

position and that the lever 24 is likewise free to turn from the position shown in Figure 3.

Furthermore, by arranging the cylindrical portion 16 to be eccentric, or shaped as a cam, as indicated by the dash-dot line 16x in Figure 2, and by providing means for manually twisting the plunger when desired, the maximum fuel delivery can be adjusted when desired.

Furthermore, electric contacts may be arranged and connected up to illuminate a pilot light in the event of the lubrication pressure failing, so as to obviate the likelihood of the driver attempting to restart the engine without investigating the trouble.

Obviously, instead of using a piston form of plunger, use may be made of a diaphragm or bellows device, or some other form of hydraulic device may be used, provision being made for its torsional control as well as for its axial movement.

What I claim as my invention and desire to secure by Letters Patent of the United States is:

1. For a fuel-injection engine, the combination with a fuel pumping unit having a main fuel control member, of a plunger having a head coacting with said member, said head having a frusto-conical portion the smaller diameter of which is adjacent an eccentric cylindrical portion, means biassing said plunger to a position in which the larger diameter of said frusto-conical portion engages said member to cut off the fuel delivery, means for applying the lubrication pressure of the engine to said plunger to force it against the biassing means so that, when the engine is running normally, said cylindrical portion engages said member to limit the maximum fuel delivery, and means for partially rotating the plunger to control the maximum fuel delivery when the engine is running normally.

2. For a fuel-injection engine, the combination with a fuel pumping unit having a main fuel control member, of a plunger having a head coacting with said member, said head having a frusto-conical portion the smaller diameter of which is adjacent a cylindrical portion, means biassing said plunger to a position in which the larger diameter of said frusto-conical portion engages said member to cut off the fuel delivery, means for applying the lubrication pressure of the engine to said plunger to force it against the biassing means so that, when the engine is running normally, said cylindrical portion engages

5 said member to limit the maximum fuel delivery, said plunger having a longitudinal peripheral groove through the frusto-conical portion to receive the adjacent end of said member, the bottom wall of said groove being nearer the axis of the plunger than the periphery of said cylindrical portion, and means for partially rotating the plunger to enable said member to enter said groove and to thus increase the maximum fuel delivery above normal when the engine is being started.

10 3. For a fuel-injection engine, the combination with a fuel pumping unit having a main fuel control member, of an angularly and axially movable plunger having a head coacting with said member, said head having a frusto-conical portion the smaller diameter of which is adjacent a cam portion, and said frusto-conical portion having a longitudinal peripheral groove in it to receive the adjacent end of said member, the bottom wall of said groove being nearer the axis of the plunger than the periphery of said cam portion, means biassing said plunger to a position in which the larger diameter of said frusto-conical portion engages said member to cut off the fuel delivery, with said groove spaced angularly from said member, means for applying the lubrication pressure of the engine to said plunger to force it axially against the biassing means so that, when the engine is running normally, said cam portion engages said member to limit the maximum fuel delivery, and means for partially rotating the plunger against said biassing means to control the maximum fuel delivery 15 when the engine is running normally and to enable said member to enter said groove to increase the maximum fuel delivery above normal when the engine is being started.
